UNITED STATES PATENT OFFICE.

FRANK SHUMAN, OF PHILADELPHIA, PENNSYLVANIA.

UTILIZING WASTE HEAT OF COMPRESSORS.

979,579.

Specification of Letters Patent.

Patented Dec. 27, 1910.

Application filed March 18, 1907, Serial No. 362,892. Renewed May 21, 1910. Serial No. 562,766.

To all whom it may concern:

Be it known that I, FRANK SHUMAN, a citizen of the United States, residing in Philadelphia, Pennsylvania, have invented 5 certain Improvements in Utilizing Waste Heat of Compressors, of which the following is a specification.

The object of my invention is to utilize 10 for the performance of mechanical work, heat due to the compression of an elastic fluid as well as waste heat of the engine used for operating the compressor, an object which I attain in the following manner, reference being had to the accompanying 15 drawing, in which:

Figure 1 illustrates one form of apparatus for carrying out my invention, and Fig. 2 a modified form of apparatus for the purpose.

20 In Fig. 1 of the drawing, 1 represents the power cylinder and 2 the compression cylinder of an apparatus for compressing air or other elastic fluid, 3 representing the inlet valve chest of the compressor with its inlet pipe 4, and 5 representing the outlet chest with its discharge pipe 6, the valve chest of the power cylinder being represented at 7, the motive fluid supply pipe at 8, and the exhaust pipe at 9.

30 The power generator, represented at 10, contains a power-developing agent having a relatively low boiling point, meaning by this a boiling point considerably lower than the temperature of the compressed fluid issuing from the cylinder 1 or of the motive power fluid exhausted from the cylinder 2, whereby the heat of these fluids will serve to vaporize the power-developing agent under such pressure as may be needed for the work 35 to be performed thereby. As instances of power-developing agents which may be effectively employed, I may mention naphtha, tetra-chlorid of carbon, di-methyl oxid, ether, ammonia, liquefied sulfurous acid gas, 40 liquefied carbonic acid gas, etc.

Usually the exhaust from the power cylinder of the compressor, especially if the latter is operated by steam, is of considerably lower temperature than the compressed 45 elastic fluid delivered by the compression cylinder 1, and for the purpose of vaporizing the power-developing agent in the generator 10, I therefore prefer to use independent pipes, that from the power cylinder 1 being coiled or otherwise disposed in the power portion of the generator while the

pipe from the compression cylinder 2 is coiled or otherwise disposed in both the upper and lower portions of the generator, the exhaust steam coil being represented at 11 and the coil containing the air or other compressed elastic fluid being represented at 12. The reason for this will be understood when it is borne in mind that the liquid power-developing agent in the generator 65 has the highest temperature at the surface and a gradually decreasing temperature from top to bottom, for instance the surface temperature may be 500 degrees F. or more, while the temperature at the bottom 70 may be 60 degrees F. or less. Loss of heat would therefore result if the exhaust pipe from the cylinder 1 entered the generator 10 at a point where the temperature of the power-developing agent had been raised by 75 the coil 12 to a degree higher than the temperature of the motive fluid escaping from the power cylinder, hence the restriction of the coil 11 to the lower portion of the generator wherein the temperature of the power-developing agent does not exceed the temperature of the exhaust fluid passing through said coil.

In many cases it may be advisable, before conveying to the generator the exhaust from 85 the power cylinder, to pass it through a jacket, such as 20, surrounding the compression cylinder, thereby increasing the temperature of the exhaust, this being especially advantageous in those cases in which the 90 temperature due to compression of the elastic fluid in the cylinder 2 is so high, that unless reduced, it will interfere with the proper operation of the compressor.

The generator has a discharge pipe 13, 95 whereby the vapor under pressure is conveyed to an engine or other apparatus in which it is to be used, and it is also provided at the bottom with a return pipe 14 through which the condensed and cooled 100 power-developing agent, after such use, is brought back to the generator for revaporation. The upper portion of the coil 12 may be extended through the vapor chamber of the generator, as shown, when it is 105 desired to superheat the vapor.

If a steam engine is the motive power agent employed for operating the compressor, the condensed steam from the coil 11 may be permitted to run to waste or back 110 to the boiler from the discharge pipe 15 of said coil, but if motive fluids other than

steam are employed which are susceptible of being reduced to a temperature below the freezing point of water, the escape from the pipe 15 may be utilized in any way which 5 its low temperature may suggest and the escape from the discharge pipe 16 of the coil 12 may be used in such a way as will obtain the desired benefit both from its pressure and low temperature.

10 The use of a single generator containing both coils 11 and 12 is not essential to my invention, as properly connected but separate generators, one containing the exhaust pipe coil and the other the compressed fluid 15 pipe coil, may be used if desired, as shown at 10^a and 10^b in Fig. 2, and while I have shown in the drawing a direct-acting engine for operating the compressor, any other desired type of engine may be used. It will 20 also be understood that no attempt has been made in the drawing to show the relative sizes or location of the different parts of the apparatus and that non-conducting coverings will be provided upon all parts of the 25 apparatus at which radiation or absorption of heat is not desired.

Although in the apparatus shown in Fig. 2, two generators are used, volumes of power developing agent in these generators are 30 connected and practically constitute one body, as in Fig. 1, the only difference being that in the apparatus shown in Fig. 1, the compressed fluid pipe coil acts upon the same portion of the agent as the exhaust 35 pipe coil, as well as upon an additional portion of the same.

I claim:

1. The mode herein described of utilizing waste heat of compressors, said mode consisting in causing the exhaust motive power fluid of the compressor engine to heat one portion of a power-developing agent having a relatively low boiling point, and causing the compressed fluid to heat to a higher temperature another portion of said agent.

45 2. The mode herein described of utilizing waste heat of compressors, said mode consisting in causing the exhaust motive power fluid of the compressor engine and the compressed fluid, conjointly, to heat one portion of a power-developing agent having a relatively low boiling point, and causing said compressed fluid to heat to a higher temperature another portion of said agent.

50 3. The mode herein described of utilizing waste heat of compressors, said mode consisting in raising the temperature of the exhaust motive power fluid of the compressor engine by heat of the compressed fluid, causing said exhaust motive power fluid, thus in-

creased in temperature, to heat one portion of a power-developing agent having a relatively low boiling point and causing the compressed fluid to heat to a higher temperature another portion of said agent.

65

4. The mode herein described of utilizing waste heat of compressors, said mode consisting in causing the exhaust motive power fluid of the compressor engine to first lower the temperature of the compressed fluid in 70 the compressor and then to heat one portion of a power-developing agent having a relatively low boiling point, and causing the compressed fluid to heat to a higher temperature another portion of said agent.

75

5. The mode herein described of utilizing waste heat of compression, said mode consisting in vaporizing, by heat of the compressed fluid, a power-developing agent having a relatively low boiling point and also 80 causing the heat of the compressed fluid to superheat the vapor under pressure thus produced.

6. The mode herein described of utilizing waste heat of compressors, said mode consisting in causing the exhaust motive power fluid of the compressor engine to heat one portion of a power-developing agent having a relatively low boiling point, and causing the compressed fluid to heat to a higher temperature another portion of said agent and 90 the vapor under pressure thereby produced.

85

7. The mode herein described of utilizing waste heat of compressors, said mode consisting in causing the exhaust motive power fluid of the compressor engine and the compressed fluid conjointly to heat one portion of a power-developing agent having a relatively low boiling point and also causing the compressed fluid to heat, to a higher temperature, another portion of said agent and 100 the vapor under pressure thereby produced.

95

8. The mode herein described of utilizing the waste heat of compressors, said mode consisting in first causing the exhaust motive power fluid of the compressor engine to reduce the temperature of the compressed fluid in the compressor, and then to heat one portion of a power-developing agent having a relatively low boiling point, and causing 105 the compressed fluid to heat to a higher temperature another portion of said agent and the vapor under pressure thereby produced.

105

In testimony whereof, I have signed my name to this specification, in the presence of 115 two subscribing witnesses.

FRANK SHUMAN.
